FIXING DEVICE

Joseph Claude Sauveil, 6 Villa d'Arcueil, Vanves, France
Filed May 23, 1962, Ser. No. 197,103
Claims priority, application France, May 23, 1961, 6,862
4 Claims. (Cl. 85—9)

The present invention relates to a new device permitting of the rigid fixing—by attachment and not by frictional adhesion—of a member of any kind on a wall of which one face is inaccessible, and therefore by working from one side only of the said wall.

In principle, this result can be obtained (as shown in FIGS. 1 to 4 which illustrate the general principle of the invention), by introducing into a hole C pierced in the wall A and in the part to be fixed B (see FIG. 1), a hooking member 1 having, on the one hand, a projecting portion 2 and, on the other, a keying orifice 3. This member 1 being passed into the hole C and having taken up the position defined in FIG. 2, can be held in place by a member 4 which fixes the locked position of the element 1, as shown in FIG. 3. This member 4 comprises a portion 5 which serves as a key, or a wedge, and a portion 6 which is supported against the member B. When mounted as shown in FIG. 3, this member 4 keeps the projecting portion 2 of the member 1 in a hooked position. It is then an easy matter to ensure the clamping of the member B on the wall A, for instance by means of a small key 7 as shown in FIG. 4.

The present invention has for its object a fixing device which employs and adapts the principle described above. The elementary parts of the device have been designed so as to create a unit which is easy to apply, the three basic elements viz: the hooking, locking and clamping members being previously mounted on each other ready for use.

The fixing device is constituted and characterized by:

- (1) A hooking member which can pass easily through the holes formed in the parts to be assembled, and having on the one hand, after the final fixing in position, a projection which engages against the inaccessible surface of the wall, and, on the other hand, an engagement for the clamping member. This engagement may be a threaded portion or a mortise or any other appropriate arrangement.

(2) A locking bushing for holding the projection of the hooking member in its engaged position. This locking bushing comprises in principle a positioning collar or flange.

(3) A conventional clamping member (such as a nut, cam, pin, key, etc.) enabling the whole assembly to be rigidly fixed together.

By way of explanation only and without any implied limitation, the description which follows will show how a fixing device according to the invention can be constructed in the particular case where it is intended to fix a part B having a thickness b on a wall A having a thickness a (see FIG. 5), the wall and the part being pierced with a hole C having a diameter c. In the form of embodiment disclosed hereafter, and corresponding to FIGS. 5 to 13 and 15, the clamping device used is a nut.

FIG. 6 shows in cross-section a form of embodiment of the fixing device according to the invention, in which there are again found the elements referred to in the description of the principle which forms the basis of the invention, namely:

- (1) A hooking member 8;
- (2) A locking and positioning bushing 9;
- (3) A clamping member, which, in the present case 70 is a nut 10.

2

These members 8, 9, 10 are equivalent to members 1, 4, 7 respectively, of FIGS. 1 to 4.

The hooking member 8 (FIG. 7) is constituted in this case by a special bolt 2 with a cylindrical head 11 (which is equivalent to the projecting portion 2 in FIGS. 2-4) eccentrically arranged with respect to the shank 12 by an amount d. The diameter of this head is slightly less than the diameter c, so as to be able to pass freely into the hole C. The shank 12 of the bolt has a diameter e and a length f. At its extremity is provided a slot 13 for receiving a screw driver.

The locking or wedging bushing 9 (FIGS. 8 and 9) comprises a skirt 14 (which is equivalent to portion 5, in FIGS. 3 and 4) the transverse section of which is that of a crescent, the external diameter of which is c, that is to say that of the hole C and of the bolt head 8, and whose internal diameter is also c, but eccentrically shifted by a certain amount g. The result is that the thickness of the skirt in its thickest portion, that is to say in the direction of the eccentricity, is also g.

It should be observed that this value g is also the maximum value of the projection to be obtained for hooking the member 8 behind the wall A. This skirt has a length h which is equal to both the parts to be assembled (a+b) plus a certain length taken as equal to half the dimension e of the diameter of the bolt 8

$$\left(\text{viz. } h = a + b + \frac{e}{2} \right)$$

The bushing 9 comprises a flange 15 (equivalent to portion 6 in FIGS. 3 and 4) having a thickness i. This flange is pierced with a hole 16 (FIGS. 8 and 9) having a diameter j permitting the passage of the bolt 8. This hole is pierced eccentrically with respect to the external machining of the skirt 14 by an amount equal to g/2 and in the same direction as the eccentricity given to the internal machining of the same skirt.

It should be noted that the centres of the circles defining the crescent of the skirt 14 are each eccentric by a quantity g/2 on each side of the centre of the hole 16 having a diameter j (FIG. 9).

In the form of embodiment disclosed of a fixing device according to the invention, the diameter of the flange is equal to 2c. In addition, the values a, b, c, d, e, f, g, h, i, j, k are chosen so as to have the following relationship:

$$g = \frac{c}{4} \quad d = \frac{g}{2} \quad e = \frac{2c}{3} \quad h = a + b + \frac{e}{2} \quad f = a + b + i +$$

50 (Height of nut 10) $i = 2 \text{ mm.}$

The clamping nut 10 is of a conventional type.

FIG. 10 of the accompanying drawing shows in cross-section a fixing device according to the invention assembled and ready for use (see also the perspective view given in FIG. 15).

It will be observed that the head 11 of the hooking member 8 is mounted as an extension of the skirt 14 of the locking bushing 9 and is held in position by the clamping effect of the nut 10, which is a light clamping action simply intended to hold the parts in position.

The fixing device thus prepared can easily be introduced into the hole C made for the purpose of fixing the part B on the wall A, and to take up the position in the hole as shown in FIG. 11.

When the fixing device is placed in the position shown in FIG. 11, it is only necessary, the bushing 9 being held in position, to rotate the hooking member 8 through 180° by means of a screw driver 17.

It will then be possible, by pulling on the nut 10, to cause the eccentric head 11 of the hooking member 8 to

slide in the eccentric bore of the bushing 9 so as to obtain the position of the parts shown in FIG. 12.

In this position, the eccentric portion of the head 11 of the hooking member 8 is applied against the inaccessible surface of the wall A at 18, and the hooking member 8 is fixed by its head in the slide of the skirt 14. It is then easy to tighten up the nut 10 and to clamp the whole assembly as shown in FIGS. 13 and 6.

A large number of alternative forms of embodiment may be given for each of the elements of the fixing device according to the invention both as regards their shapes and their proportions. All these alternative forms remain within the scope of the present invention, provided they comprise at least the three basic elements on which the said patent application is based, namely a hooking member, a locking member and a clamping member.

In this respect, the form of embodiment shown in FIG. 14 should be taken in consideration; in that figure the hooking member is constituted by an eccentric cylindrical nut 19, and the clamping device is a conventional screw 20.

In the above example (corresponding to FIGS. 5-13 and 15) a nut 10 provides the clamping of the assembly, but it is quite obvious that it is possible to employ either a key 7 (as shown in FIGS. 4 and 16, or a cam 21 as in FIG. 17), or any other clamping device, while remaining within the scope of the present invention.

Similarly, by utilizing the above-defined technique, it is possible to produce fixing devices according to the invention which can be fitted into holes of all shapes (viz. square, rectangular, polygonal, etc.) while again remaining within the scope of the invention.

The invention is directed to:

(1) Fixing devices designed and constructed according to the technique described above and the example of construction which has been given.

(2) The variations of construction having the same technique and the same principles and employing the same basic elements.

(3) The various applications and combinations of known means employed in the construction.

(4) By way of new industrial products, the fixing bolts of all sizes and for all uses as constructed in accordance with the invention.

I claim:

1. A fixing device for fixing a member of any kind rigidly on a wall, the rear face of which is inaccessible, with a hole pierced in both said member and the wall, comprising:

a hooking and clamping unit having a cylindrical threaded shank adapted to pass through the wall and provided, at one end, with a cylindrical projection having a diameter greater than the diameter of said shank and its axis parallel to the axis of said shank and eccentrically disposed with respect to said shank and adapted to engage against the inaccessible face of the wall, and at its other end, with a clamping member, one of said projection and clamping members being screwed on said shank and the other being integral with said shank;

a cylindrical locking member comprising a flange pierced with a hole permitting the passage of said shank and having a greater radius than the radius of said cylindrical projection, and a skirt having a crescent shaped cross-section extending from said flange with two circular edges of the same radius with that of the cylindrical projection and the concave portion of the crescent substantially facing said shank whereby said one of said projection and clamping members screwed on said shank being caused to move with respect to said shank which renders said fixing device suitable for various continuous values, starting from nearly zero, of the total thickness of the member to be fixed and the wall, and said cylindrical projection can be securely supported on said skirt.

2. A fixing device for fixing a member of any kind rigidly on a wall, the rear face of which is inaccessible, with a hole pierced in both said member and the wall, comprising:

5 a hooking and clamping unit having a cylindrical threaded shank adapted to pass through the wall and provided, at one end, with a cylindrical projection having a diameter greater than the diameter of said shank and its axis parallel to the axis of said shank eccentrically disposed with respect to said shank and integral with same and adapted to engage against the inaccessible face of the wall, and at its other end, with a clamping nut adapted to engage said threaded shank;

10 a cylindrical locking member comprising a flange pierced with a hole permitting the passage of said shank and having a greater radius than the radius of said cylindrical projection, and a skirt having a crescent-shaped cross-section extending from said flange with two circular edges of the same radius with that of the cylindrical projection and the concave portion of the crescent substantially facing said shank, whereby said nut can be caused to move along said shank which renders said fixing device suitable for various continuous values, starting from nearly zero, of the total thickness of the member to be fixed and the wall, and said cylindrical projection can be securely supported on said skirt.

15 3. A fixing device for fixing a member of any kind rigidly on a wall, the rear face of which is inaccessible, with a hole pierced in both said member and the wall, comprising:

20 a hooking and clamping unit having a cylindrical threaded shank adapted to pass through the wall and provided, at one end, with a cylindrical projection having a diameter greater than the diameter of said shank and its axis parallel to the axis of said shank adapted to engage said threaded shank and eccentrically disposed with respect to same and adapted to engage against the inaccessible face of the wall, and at its other end, with an integral clamping head; a cylindrical locking member comprising a flange pierced with a hole permitting the passage of said shank, and having a greater radius than the radius of said cylindrical projection, and a skirt having a crescent-shaped cross-section extending from said flange with two circular edges of the same radius with that of the cylindrical projection and the concave portion of the crescent substantially facing said shank, whereby said projection can be caused to move along said shank which renders said fixing device suitable for various continuous values, starting from nearly zero, of the total thickness of the member to be fixed and the wall, and said cylindrical projection can be securely supported on said skirt.

25 4. A fixing device for fixing a member of any kind rigidly on a wall, the rear face of which is inaccessible, with a hole pierced in both said member and the wall, comprising:

30 a hooking and clamping unit having a cylindrical threaded shank adapted to pass through the wall and provided at one end, with a cylindrical projection having a diameter greater than the diameter of said shank and its axis parallel to the axis of said shank eccentrically disposed with respect to said shank and integral with same and adapted to engage against the inaccessible face of the wall, and at its other end, with a transversal slot adapted to receive a screw driver and with a clamping nut adapted to engage said threaded shank;

35 a cylindrical locking member comprising a flange pierced with a hole permitting the passage of said shank and having a greater radius than the radius of said cylindrical projection, and a skirt having a crescent-shaped

cross-section extending from said flange with two circular edges of the same radius with that of the cylindrical projection and the concave portion of the crescent substantially facing said shank, whereby said nut can be caused to move along said shank which renders said fixing device suitable for various continuous values, starting from nearly zero, of the total thickness of the members to be fixed and the wall, and said cylindrical projection can be securely supported on said skirt.
